PORTABLE WASHING STAND

Roman Zakaski, South Charleston, W. Va., assignor to Monty Enterprises, Inc.

Filed Mar. 19, 1971, Ser. No. 126,388

Term of patent 7 years

Int. Cl. D23—02

U.S. Cl. D23—48

FIG. 1

FIG. 3

FIG. 1 is a perspective view of a portable washing stand embodying my new design;

FIG. 2 is another perspective view thereof taken from the side opposite that shown in FIG. 1; and

FIG. 3 is an enlarged side elevational view thereof with the support pole broken away for convenience of illustration.

I claim:

The ornamental design for a portable washing stand, as shown.
